DESIGN FOR A CARPET-PATTERN.

Specification forming part of Design No. 5,444, dated December 19, 1871.

To all whom it may concern:

Be it known that I, DAVID McNAIR, of the city of Lowell, county of Middlesex and State of Massachusetts, have invented and produced a new and original Design for a Pattern to be Inwrought into Two or Three-Ply, Ingrain, and other Carpeting in such colors as may be desired; and I do hereby declare that the photographic print accompanying this specification does give and convey to any one skilled in the art of carpet-weaving a more definite and thorough description of the nature of my invention than it is in the power of language otherwise to convey, and it is suffi-

cient to enable any one skilled in the art of carpet-weaving to use my invention.

What I claim as my invention, and desire to secure by Letters Patent, is—

The configuration of the design hereunto annexed, when made by being inwrought into two or three-ply, ingrain, or other carpeting in the form similar to the photographic print accompanying this specification.
